METHOD AND MEANS FOR PRODUCING HIGH DEGREE TELEVISION PICTURE BRILLIANCE

Russell J. Callender, St. Paul, Minn.

Application August 20, 1951, Serial No. 242,671

12 Claims. (Cl. 315—14)

This invention relates to television receiving systems and pertains more particularly to a method and apparatus for obtaining a high degree of picture brilliance.

One important object of the invention is to produce a televised image of such brilliance that it may be readily enlarged and projected upon a large viewing screen for public demonstration.

Another important object of the invention is to obtain a high degree of picture brilliance without the concomitant disadvantage of rapid deterioration of the cathode ray tube's luminescent screen, such deterioration being commonly referred to as "burning" or "browning." In this connection, I have found it possible to increase the brilliance of a cathode ray tube by as much as 50 to 100% without noticeable browning of the screen during the expected life of the tube.

A further object of the invention is to produce a focusing and electron accelerating arrangement wherein the electron beam stays in focus over a wider angle of beam swing. In other words, I obtain excellent focusing at the fringe of the picture. In this connection, it is also to be noted that my system stays in focus under wide fluctuations of anode voltages caused by large changes in beam current.

A still further purpose of the invention resides in the provision of a cathode ray tube that is no more complex than tubes now in general use, and which can be sold at approximately the same price.

Another object of the invention is to provide a cathode ray tube and associated apparatus suitable for installation in existing television sets with little adaptation thereof.

Still another object of the invention is to obtain a perfect beam current cut-off, thereby producing an improved picture contrast.

It is also within the purview of this invention to obtain a better utilization of the electrons emitted from the cathode.

With the foregoing and other objects in view, which will be manifest in the following detailed description and specifically pointed out in the appended claims, reference is had to the accompanying drawings for an illustrative embodiment of the invention wherein:

Figure 1 is a schematic representation of a cathode ray tube and associated details presented in elementary form in order to provide an understanding of the basic concepts involved in the invention; and

Figure 2 is an end view of the screen of the tube depicted in Figure 1, a conventional picture area being shown in dotted outline and my recommended increased picture area being shown in dash outline.

Referring now to the drawing, there is shown a cathode ray tube A adapted for use in the practicing of my invention. The tube A includes a glass envelope 10 having a heater filament 12 at one end which is in heat transfer relationship with a cathode 14. The flow of electrons emitted by the cathode 14 is first controlled or regulated by a control grid 16 containing in circuit therewith a

2

derivative 18 of the television signal being transmitted. Axially positioned with respect to the control grid 16 is a first anode 20 provided with a flared end 22. A second anode 24 is disposed beyond the anode 20, this anode 24 being generally cylindrical and containing therein a plurality of annular elements 26. A conductive coating 28, such as Aquadag, serves as a third anode, the coating being applied to the inner surface of the glass envelope 10. It will be observed from the drawing that the coating 28 is cylindrical adjacent the end toward the second anode 24, bellng outwardly into conductive relationship with a luminescent screen 30 applied to the large end of the envelope 10. For purposes well understood in the Kinescope art, the screen is preferably aluminized on its inner surface.

Outwardly of the neck of the envelope 10 is circumposed a magnet element 32 which may be a permanent magnet, an electromagnet, or a combination electron-permanent magnet. The magnet 32 may be circumscribed about an insulating carrier sleeve 33 which is in sliding engagement with the envelope 10. In this way the sleeve 33 may be moved axially with respect to the envelope 10 to produce an optimum focus of the electron beam being accelerated by the anodes 24 and 28. In order to obtain the proper physical center of the electron beam as it strikes the screen 30, I provide an annular steel element 34 having a bore 35 of larger diameter than the outer diameter of the envelope 10. It will be apparent that the attraction of the magnet 32 will retain the annular steel element 34 in the desired position, such position once having been obtained by adjustment of said annulus in a plane normal to the general axis of the envelope 10.

The invention envisages the employment of horizontal and vertical magnetic deflection coils 36 and 37 which operate in a known manner to produce the desired scanning of the electron beam over the surface of the screen 30. As is customary in television receiving sets, the coils 36 and 37 may be provided with inductive shunts by which the magnetic field intensity of the coils 36 and 37 may be varied. Later on it will be explained that the coils 36 and 37 are adjusted to produce a magnetic field of such intensity as to partially deflect the electron beam off the luminescent screen 30.

For the purposes of simplicity the means for producing the desired potentials on the various cathode ray tube elements above referred to has been illustrated as a potentiometer B. In actual practice, however, the potentials exemplified will be derived from appropriate points in the television receiver circuit itself. It will be course be understood that the potentials set forth are illustrative only, although they do represent voltage values which produce extremely desirable operating characteristics and are therefore recommended.

The potentiometer B is grounded at 38, thereby affording a negative bias of from 90 to 100 volts at 39, such a negative bias when applied to the control grid 16 and influenced by the incoming signal 18 producing the necessary change in electron emission to thereby provide an electron beam of the proper intensity variant. The cathode 14 is connected to the potentiometer at 40 which point is at an approximate potential level of 25 volts. The first anode 20 is adjustable over a range of from approximately 150 to 300 volts, as indicated by its potentiometer connection at 42. In practice, the potential of the anode 20 is adjusted for beam cut-off, or proper black picture level for the "no signal" bias of the control grid 16. The anodes 24 and 28 are connected to the potentiometer at 44 and 45 to provide accelerating potentials of 12,000 to 15,000 volts and 27,000 to 31,000 volts, respectively. In order to properly insulate the anode lead 46, which passes through the glass envelope 10, I prefer-

ably employ insulation 47 around that region of the envelope, such insulation 47 suggestively being in the form of tape and of sufficient total thickness to properly insulate the tube A for the range of voltages applied to this locus.

In operation, the tube elements 14, 15, 20, 24 and 23 are adjusted to the proper voltage values, the specific values and ranges thereof given above being typical for a representative application. As previously mentioned, it will be noted that the potential of the anode 20 is such as to provide beam current cut-off when no signal is being received. With the tube A thus placed in operation, the coils 36 and 37 are adjusted to a field strength such as to swing the electron beam through a greater spherical angle than is normally done. For example, the normal area covered by the scanning beam is represented by the dotted rectangle 48, while the increased area subtended by the greater spherical angle of electron projection is designated by the numeral 50. It will be apparent from Figure 2 that certain extreme portions of the produced image are lost in that the electron beam will strike sections of the tube A which are either not coated with fluorescent material or which are on the sides of the tube head and therefore not directly visible from a position confronting the screen 30.

After setting the beam in scanning motion, as above outlined, the magnetic element 36 is moved into the best focusing relationship obtainable. As a general rule, the magnet 32 is moved toward the screen 30 when relatively large electron accelerating voltages are employed and in the opposite direction when smaller voltages are utilized. The magnet 32 therefore should be designed for the field strength that will give the most optimum focusing effect. However, it will be appreciated that for a magnet having a particular field strength, the voltage impressed upon the anode 24 may be changed to provide similar focusing. But since a change of the voltage of the anode 24 influences the brilliancy of the image on the screen 30, it is preferable to adjust the potential of the anode 24 for the desired brilliancy, and to select a magnet of the proper strength for the potential used. By employing a combined permanent and electro-magnet element, the strength of the magnet 32 may be adjusted to likewise produce the focus. Also, if desired, after selection of the voltage at the anode 24, the focusing may be obtained by increasing the length of magnetic path through which the electrons must flow by adding magnetic rings to the magnet 32.

With the above described arrangement, it is to be noted that not only does my system provide improved performance, most notably observed in greater brilliancy and good focusing adjacent the fringe areas of the picture, but at the same time it eliminates the need for a cooling fan, usually required in large picture projection, while prolonging the usable life of the cathode ray tube.

In accordance with the patent statutes, I have described the principles of construction and operation of my method and means for producing high degree television picture brilliancy, and while I have endeavored to set forth the best embodiment thereof, I desire to have it understood that obvious changes may be made within the scope of the following claims without departing from the spirit of my invention.

I claim:

1. In combination with a television receiver, a cathode ray tube comprising a cathode element, a control grid element, first, second and third cylinder anode elements in straight gun alignment and electrostatic and magnetic field focusing means circumscribing the second anode element, said several anode elements being of progressively greater potentials with respect to said cathode element.

2. In a television receiver, a cathode ray tube comprising in combination a cathode element, a control grid element, a first anode element having a potential applied thereto for biasing the electron beam to cut-off, a second anode element having a potential of from about 12,000

to about 15,000 volts applied thereto, a third anode element having a potential of from about 27,000 to about 31,000 volts applied thereto, magnetic means circumjacent said second anode element, for focusing the electron beam, and magnetic deflecting coils having sufficient field strength to deflect said beam beyond the normal viewing limits of the cathode tube screen, whereby the refractive power of the second electrode accomplishes focus of the electron beam electrostatically and magnetically at increased acceleration potential to obtain increased picture brilliancy without noticeable browning of said screen.

3. A method of producing an enlarged televised image having a high degree of picture brilliancy with a cathode ray tube provided with cathode, control grid, first, second, and third anode elements, and beam deflecting means, the method comprising the steps of subjecting the third anode element to a relatively high operating potential, the second anode element to an intermediate potential and the first anode element to a relatively low potential each of said steps progressively increasing the velocity of an electron beam from said first to said third anode elements, said relatively low potential being sufficient to bias the cathode ray tube beam to cut-off, and focusing the cathode ray tube beam adjacent the locus of the second anode-element to produce a well defined image on the screen of said tube.

4. The method of claim 3 in which the second anode element is subjected to a potential approximating one half of the potential applied to said third anode element.

5. The method of claim 3 in which the beam deflecting means is adjusted to a strength which will deflect the beam into a region beyond the viewable limits of the tube screen, thereby producing a picture containing only the more central portion of the televised image.

6. A method of producing an enlarged televised image having a high degree of picture brilliancy which includes accelerating an electron beam at one potential, then to a greater potential and then to a still greater potential, and creating electrostatic and magnetic refracting fields to focus said electron beam on a fluorescent screen without changing the length of the focal distance and said last mentioned potential providing increased acceleration to said electron beam to produce a well defined image on said fluorescent screen without noticeable burning or browning of the screen.

7. A method of producing a relatively enlarged and brilliant television picture which comprises the steps of increasing and accelerating the velocity of an electron beam through several stages including an intermediate stage, controlling the negative ions of the said beam at said intermediate stage to avoid browning of the picture screen by the increased velocity of the said beam, focusing the said beam adjacent one of said intermediate stage, and deflecting said beam beyond the normal viewing limits of a luminescent screen to thereby prevent said electron beam from striking the screen adjacent the marginal portions of the complete picture being televised by the transmitting station.

8. In combination, a television receiving system provided with an enlarged public viewing screen upon which a picture is obtained with a high degree of brilliancy without noticeable burning or browning of the screen during the life of the tube, said cathode ray tube having a cathode element, a control grid element, a series of spaced anode elements for stepping up the voltage on the order of from 90 volts to 100 volts at the cathode to the order of 27,000 volts to 31,000 volts at the screen, one of said anode elements positioned in aligned intermediate relationship to the other of the anode elements and carrying a voltage on the order of 12,000 volts to 15,000 volts in the said series, an axially adjustable magnetic focusing element about said tube circumscribing said intermediate anode, an insulation mounting for said magnetic focusing element, and a deflection yoke cooperative-

ly producing an optimum focus of the election beam being accelerated toward said screen by said intermediate anode and another anode in spaced relationship thereto adjacent said screen.

9. The structure of claim 8 wherein the said anode between said intermediate anode and said screen is in conductive relationship with said screen and connected to an insulated lead in. 5

10. The structure of claim 9 wherein the magnetic focusing element is a combined adjustable permanent and electromagnet means. 10

11. In combination with a picture screen viewing television cathode ray tube having a cathode element, a control grid element, a plurality of special aligned anode elements of progressively greater potentials with respect to said cathode to produce an accelerated election stream, a magnetic focusing element circumscribing an anode element in said alignment in spaced relationship to an anode adjacent said picture screen, a deflection yoke, and an insulation enveloping said tube adjacent the region of the screen to prevent arc over therefrom of the accelerated high voltage. 15 20

12. The structure of claim 11 including a third anode enclosed by said insulation and said tube and an anode lead-in which passes through the said insulation and into said television tube.
